Primary Examiner — David Muller(74) *Attorney, Agent, or Firm* — Faegre Baker Daniels LLP**CLAIM**

The ornamental design for a wire bonding ceramic capillary, as shown and described.

DESCRIPTION

FIG. 1 depicts a first perspective view of a wire bonding ceramic capillary.

FIG. 2 depicts a second perspective view thereof;

FIG. 3 depicts a top plan view thereof;

FIG. 4 depicts a side elevation view thereof; and,

FIG. 5 depicts a bottom plan view thereof.

The broken lines in the drawings illustrate environmental structure on the article and form no part of the claimed design.
